[57] CLAIM

The ornamental design for a child swing, as shown.

DESCRIPTION

FIG. 1 is a perspective view of a child swing showing my new design;

FIG. 2 is a right side elevational view thereof; the left side elevational view being a mirror image thereof;

FIG. 3 is a rear elevational view thereof; the front elevational view being a mirror image thereof;

FIG. 4 is a top plan view thereof; and,

FIG. 5 is a bottom plan view thereof.

FIGS. 2 through 5 are shown in enlarged scale for clarity.

FIG. 1

FIG. 2

FIG. 4

FIG. 3

FIG. 5
